UNITED STATES PATENT OFFICE.

BROR JOHANNES BENGTSSON, OF KÄLLELED, SWEDEN.

GRINDING-MACHINE.

1,224,593.

Specification of Letters Patent.

Patented May 1, 1917.

Application filed September 15, 1915. Serial No. 50,818.

To all whom it may concern:

Be it known that I, BROR JOHANNES BENGTSSON, engineer, a subject of the King of Sweden, residing at Källered, in the county of Göttenborg and Bohus and Kingdom of Sweden, have invented new and useful Improvements in Grinding-Machines, of which the following is a specification.

This invention relates to tool grinding machines and particularly to hand operated machines, and has for its general object to provide a compendious and easily operated device suited for general use, even by those not skilled in the handling of grinding machines, such as are commonly on the market.

More especially this invention has for its object to provide handy grinding machines which will occupy a reduced space without affecting the grinding power, thus rendering them adaptable for use anywhere, also to be brought in a bag by workmen who have to do their work at a distance from their workshop proper.

Another object is to provide the grinding machine with tool rests or holders which makes it easy for the laborer even if not skilled in the use, to grind knives, drills or other small tools with accuracy, including the angle of the point of spiral drills, which is always a rather difficult job for unskilled people.

In carrying my invention into effect I employ a grinding wheel on a horizontal spindle, rapidly rotated by means of a handle actuating a worm wheel with teeth arranged radially or nearly radially on the one side surface of the wheel, which teeth mesh with a worm attached to the spindle of the grinding wheel. The machine, further, is provided with means for attaching to it holders or tool rests which will enable tools of various characters to be readily treated by the machine and an accurate position, in relation to the grinding wheel, secured.

A structural embodiment of the invention is illustrated in the accompanying drawing which will now be clearly described.

In the drawing Figure 1 is a side elevation of the machine, partly in section, Fig. 2 a vertical cross section, Fig. 3 a horizontal view of a part of the machine, Fig. 4 a side view of a part of the machine with the holder for grinding of drills applied to it, Fig. 5 illustrates materially the same parts as in Fig. 4, but viewed at right angles

thereto; Fig. 6 is a cross-section through the drill holder with a drill therein and Fig. 7 a perspective view of the main parts of the drill holder when separated and placed in front of each other in such a position as they would have when ready to be connected.

The machine consists in a frame or casing *h* with a thumb screw *i* for clamping the machine in the usual manner to a bench *k* or the like. In a bearing or hub portion *F* of the casing is rotatably mounted a horizontal spindle *f*, which, at its free end supports a toothed wheel *d* with the teeth *g* arranged on the one side surface in somewhat the same manner as on a bevel tooth wheel, though the wheel may be of a cylindrical and not a bevel shape. These radially or nearly radially directed teeth *g* mesh with a worm *c* on a horizontal spindle *b*, rotatable in sleeves or bearings *C, D* in the casing *h*. According to this invention and as a consequence of the described position of the teeth *g* the worm *c* is situated across the said side surface of the wheel *d*, in contradistinction to the manner usually employed in connection with worm gearings, where the worm is situated tangentially to the circumference of the worm wheel.

The one end of the spindle *b* carries a grinding wheel *a* of emery or other suitable material and the machine is brought into rotation by means of a hand driven crank *e* actuating the wheel *d* and by reason of the worm gearing the grinding wheel *a* will be rotated at a high speed.

The tool to be ground is placed on a table or tool rest *m* which is arranged so that it can be adjusted to and from the grinding wheel *a* by means of a set screw *L* and an open slot 10.

The machine is provided further with a special tool rest *m* for grinding knives or similar implements, such rest *m* being pivoted on a pivot *n* in a bracket *o*, which is adjustable up and down in relation to the grinding wheel by means of an open slot 11 and a set screw 12. For the pivotal adjusting of the rest *m* there is employed a set screw *p*, screwed through the rest and acting against a bracket *r* on the casing *h*. A prong *q* on each side of the rest *m* protects the rest from undue contacts with the grinding wheel proper.

On each side of the grinding wheel the tool rest *m* is provided with a pair of balls 110

- or otherwise rounded parts t , the two parts in each pair being situated above and directed toward each other and forming a guide or grip for the knife 8 that is to be treated in the machine and for that reason is placed with the edge between the parts t . The upper ball or part t in each pair can be pressed against the knife by means of set screws v, x .
- 10 The described device makes it very easy even for an unskilled hand to grind a knife to an accurate angle along its whole edge, as the workman only has to place the knife between the balls or parts t and to adjust the
- 15 tool rest m by means of set screws 12 and p to the desired position in relation to the grinding wheel, after which he has merely to slide the knife to and fro into the guide formed by the balls or parts t .
- 20 The machine is also provided with a handy device for the grinding of drills, which device comprises a holder of two parts A and B , the part A of which is adapted to be pivotally fitted to the machine by means of the same pivot n as the knife rest m , when said rest has been removed, and to be adjusted to and from the grinding wheel by means of a set screw P of the same character and arrangement as the above described set screw p . Though the fastening arrangement proper of the part A is not fully shown in the drawing it may be clearly understood by comparing Figs. 4 and 5 with Fig. 2.
- 25 The other part B of the holder consists of a clamping device for the drill 4 to be treated and comprises two cheeks 1 and 2 each provided with a plurality of prismatic teeth 3 so arranged that they fit into each other, engaging around the drill 4 when placed together as shown clearly in the Fig. 6. The two cheeks are rigidly held together in this position by means of a screw clamp 5 with a thumb screw 13 . The part B is provided with means which enable it to be pivotally fitted to the part A in such a manner that the drill 4 rests with its point against the grinding periphery of the grinding wheel a under precisely the angle required for its working edge, (Fig. 4). In this position the holder B can be oscillated, around the means which connects it to the part A , with the working edge of the drill remaining in contact with the grinding surface of the wheel a thus making it possible to give the drill the desired conical working surface.
- To effect this it is necessary to employ two such pivotal fastening means arranged in such relation that the holder B can be shifted so as to treat the two opposite edges of the drill. The said means are in the drawing illustrated as comprising cylindrical prongs $6, 7$, one on each cheek 1 and 2 which prongs are inclined toward their respective cheeks in such a way, that when the cheeks are clamped together, the prongs $6, 7$ stand at the same angle to each other as the angle required for the drill (see Fig. 4). Carried on the part A there is a hub or sleeve y in which one of the prongs $6, 7$ can be temporarily inserted and oscillated as described above. When the one side of the drill is completed, the mentioned prong 6 (or 7) is removed from the sleeve y , the part B turned over a half turn, and the other prong 7 (or 6) inserted into the sleeve y . Thus the accurate angle of the point of the drill is secured.
- Though I have described and illustrated the holder A — B as comprising prongs 6 and 7 on the part B pivotable in a sleeve y in part A , I do not limit myself to this special embodiment as these parts can be varied in many ways without departing from the invention. For instance, the sleeve y in part A may be replaced by a pin, and the prongs $6, 7$ in part B by sleeves, it being understood that the parts are arranged and situated in such relation to each other that the clamp B can be pivotally mounted to the part A in a similar manner as stated above.
- To facilitate the manipulation of the clamp B when the drill is to be inserted between or removed from the clamp B , the latter can be provided with some handy spring grip of any arbitrary shape, which is not illustrated in the drawing as it belongs not to the invention proper. This spring grip preferably may be of such a type that it permits the two cheeks 1 and 2 to be held, with the one hand, pressed together around the drill 4 , while the other hand is free to screw or unscrew the clamping thumbscrew 13 .
- Having thus described my invention what I claim as new and desire to secure by Letters Patent is:—
1. In a grinding machine, the combination of a frame, a grinding wheel rotatably mounted thereon, a clamping device for holding a drill, projections on said clamping device disposed at the same angle to each other as the angle required for the point of the drill, and means on said frame pivotally receiving said projections alternatively for the purpose set forth.
  2. In a grinding machine, the combination of a frame, a grinding wheel rotatably mounted thereon, a clamping device for holding a drill, a sleeve member adjustably mounted on said frame, a pair of cylindrical projections on said clamping device arranged at substantially 90° to each other and each adapted to rotatably engage in said sleeve for the purpose set forth.
  3. In a grinding machine, the combination of a frame, a grinding wheel rotatably mounted thereon, a clamping device for holding a drill, and means for adjustably

supporting said clamping device upon said frame, said clamping device comprising two jaw members each having a plurality of prismatic gripping teeth adapted to engage 5 between the teeth of the other and said teeth being cut away to form a central opening for the drill which is clamped therebetween, and each pair of gripping teeth which lie in a common plane at right angles to the

drill being on opposite jaws and on diamet- 10 rically opposite sides of the drill.

In testimony whereof I affix my signature in presence of two witnesses.

BROR JOE ANNES BENGTSSON.
